UNITED STATES PATENT OFFICE

JOSEPH C. FRIEND, OF ASHTABULA, OHIO

ADJUSTABLE REAMER GRINDING CLEARANCE GAUGE

Application filed December 2, 1931. Serial No. 578,588.

My invention relates to an adjustable reamer grinding clearance gauge designed primarily for the purpose of adjusting the cutting clearance of all types of reamers which are about to be ground on the reamer grinder, but it is to be understood that a gauge, in accordance with my invention may be employed in any connection for which it is found applicable.

The essential objects of my invention are to provide, a gauge of such class capable of maximum accuracy for producing a uniform cutting edge and clearance on tools of the reamer type; for adjusting the desired cutting clearance on straight, spiral, expanding or solid reamers; capable of being employed to adjust the cutting clearance on cylinder boring machine cutting heads and for other reaming and cutting tools; insuring for accurate adjustment for various sizes of reamers before or after the reamer is inserted for grinding; to insure proper adjustment to prevent damage to the tool; requiring no skill in making the desired adjustments; and to attain these ends in a strong, durable, compact, thoroughly efficient, expeditiously adjusted, conveniently operated, readily installed and inexpensive structure.

To the above ends essentially and others which may hereinafter appear, my invention consists of such parts and such combination of parts which fall within the scope of the invention as claimed.

In the drawing:

Figure 1 is a top plan view of a gauge in accordance with my invention.

Figure 2 is a longitudinal sectional view thereof.

Figure 3 is a section on line 3—3 Figure 2.

Figure 4 is a section on line 4—4 Figure 2.

Referring to the drawing, 1 denotes a supporting post or support which is adapted to be anchored stationary to maintain the gauge in set position by any suitable clamping means, not shown. One end of the post 1 has a reduced peripherally threaded extension 2.

The gauge includes a carrier 3, preferably of polygonal cross section and which is formed for a portion of its length with a pass-

sage 4 of square outline extending from its outer end 5 to a point between its transverse median and its inner end 6. The carrier 3 is also formed with a lengthwise extending opening having a tapered portion 7 and a portion 8 of uniform diameter, the former merging into the outer end of passage 4 and the latter extended from end 6 to said tapered portion 7. The carrier 3 in proximity to end 5 is formed with a peripheral socket 9 having its wall threaded and engaging with the latter is the threaded extension 2 for coupling the carrier 3 and post 1 together. Between the end 5 of carrier 3 and the transverse median of the latter there is provided a transverse opening 10 communicating with passage 4 and having a threaded wall. The opening 10 preferably is in that side of the carrier opposite the side in which is arranged socket 9. The carrier 3 in proximity to end 6 is formed with a transverse opening 11 communicating with portion 8 of the lengthwise opening and having a threaded wall.

Adjustably mounted in the carrier 3 within the passage 4 and the portions 7 and 8 of the lengthwise opening, as well as extending from the ends 5 and 6 of the carrier 3 is a gauge bar 12 formed of an outer or forward part 13 of square cross section and a reduced rear part 14 of circular cross section having peripheral threads. The part 13 has a scale of graduations on one side, as at 13', extends from end 5 and has its outer end formed with a lengthwise socket 15 having a threaded wall. The part 14 extends from end 6.

A reamer head 16 has a reduced rearwardly extending peripherally threaded extension 17 which threadededly engages with the wall of socket 15 for coupling the head and bar 12 together. The head 16 carries the reamer blade 18.

Mounted upon and threadededly engaging with part 14 of bar 12, as well as extending into the carrier from the end 6 is an adjusting nut 19 of the sleeve type. The nut comprises an outer part and an inner part 20, 21 respectively, the former being of greater diameter than the latter to provide the nut 19 with an annular peripheral shoulder 22. The part 21 extends into the carrier 3 and has a

peripheral groove 23 of V-shape cross section. The shoulder 22 opposes end 6 of carrier 3.

Extending through opening 10, as well as threadedly engaging with the wall and binding against one side of part 13 of bar 12 for locking the latter in adjusted position is a locking screw 24 formed with an enlarged head 25 providing a finger or thumb grip to facilitate the adjusting of the screw to and from binding or locking position with respect to bar 12. Extending through, as well as threadedly engaging with the wall of opening 11 is a coupling screw 26 having a pointed end 27 permanently seating in groove 23, the latter in connection with the end 27 of screw 26 revolvably couples nut 19 to carrier 3. A lock nut 26' is provided for screw 26.

Secured within the periphery of carrier 3 and extended from the end 5 of the latter is an indicating pointer 28 which associates with the graduations 13' for determining the adjusted position of the gauge bar 12.

In order to make an adjustment of the gauge, the locking screw 24 is loosened by hand, thereby releasing the gauge bar 12, then by revolving the nut 19 in a clockwise or anti-clockwise direction the bar 12 will be shifted forward or backward through the carrier 3 to whatever adjustment is desired according to the size of the reamer or tool to be ground, the adjustment being indicated by the pointer on the scale 13'. After the desired adjustment is reached, the locking screw 24 can be tightened very readily by hand without disturbing the adjustment.

What I claim is:—

1. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer portion and an inner part, said inner part being peripherally threaded, said outer part being formed at its outer end with means for coupling a tool head therewith, an indicating pointer secured to and extended from the outer end of the carrier and associated with said scale, revolvable means extending into the inner end of the carrier, revolvably coupled to the latter and threadedly engaging with the inner part of said bar for adjusting the latter, and locking means connected to the carrier for said bar.

2. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded,

said outer part being formed at its outer end with means for coupling a tool head therewith, an indicating pointer secured to and extended from the outer end of the carrier and associated with said scale, revolvable means extending into the inner end of the carrier and threadedly engaging with said inner part of said bar for adjusting the latter, said revolvable means having a peripheral groove, means connected to the carrier and extending into said groove for revolvably connecting said bar adjusting means to the carrier, and releasable locking means for the bar.

3. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolvable means extending into the inner end of the carrier, revolvably coupled to the latter and threadedly engaging with the inner part of said bar for adjusting the latter, locking means connected to the carrier for said bar, and a post connected to said carrier in proximity to one end thereof.

4. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolvable means extending into the inner end of the carrier and threadedly engaging with said inner part of said bar for adjusting the latter, said revolvable means having a peripheral groove, means connected to the carrier and extending into said groove for revolvably connecting said bar adjusting means to the carrier, releasable locking means for the bar, and a post connected to said carrier in proximity to one end thereof.

5. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being

formed with an outer part and an inner part, said inner part being peripherally threaded, said outer part being formed at its outer end with means for coupling a tool head therewith, an indicating pointer secured to and extended from the outer end of the carrier and associated with said scale, revolute means extending into the inner end of the carrier, revolutely coupled to the latter and threaded-
ly engaging with the inner part of said bar for adjusting the latter, locking means connected to the carrier for said bar, said inner part being of circular cross section, said bar having its outer part of square cross section, and said bar being of greater length than the carrier.

6. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolute means extending into the inner end of the carrier and threadedly engaging with said inner part of said bar for adjusting the latter, said revolute means having a peripheral groove, means connected to the carrier and extending into said groove for revolvably connecting said bar adjusting means to the carrier, releasable locking means for the bar, said inner part being of circular cross section, said bar having its outer part of square cross section, and said bar being of greater length than the carrier.

7. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolute means extending into the inner end of the carrier, revolutely coupled to the latter and threadedly engaging with the inner part of said bar for adjusting the latter, locking means connected to the carrier for said bar, a post connected to said carrier in proximity to one end thereof, said inner part being of circular cross section, said bar having its outer part

of square cross section, and said bar being of greater length than the carrier.

8. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolute means extending into the inner end of the carrier and threadedly engaging with said inner part of said bar for adjusting the latter, said revolute means having a peripheral groove, means connected to the carrier and extending into said groove for revolvably connecting said bar adjusting means to the carrier, releasable locking means for the bar, a post connected to said carrier in proximity to one end thereof, said inner part being of circular cross section, said bar having its outer part of square cross section, and said bar being of greater length than the carrier.

9. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolute means extending into the inner end of the carrier, revolutely coupled to the latter and threadedly engaging with the inner part of said bar for adjusting the latter, locking means connected to the carrier for said bar, and said revolute means having a peripheral shoulder opposing the inner end of the carrier.

10. A gauge for the purpose set forth comprising, an elongated hollow carrier having an outer end and an open inner end, an adjustable gauge bar slidably mounted in the carrier and having one side provided with graduations, said bar projecting from the ends of the carrier, said gauge bar being formed with an outer part and an inner part, said inner part being peripherally threaded, said outer part being formed at its outer end with means for coupling a tool head therewith, an indicating pointer secured to and extended from the outer end of the carrier and associated with said scale, revolute means

extending into the inner end of the carrier and threadedly engaging with said inner part of said bar for adjusting the latter, said revoluble means having a peripheral groove, 5 means connected to the carrier and extending into said groove for revolvably connecting said bar adjusting means to the carrier, releasable locking means for the bar, and said revoluble means having a peripheral shoulder 10 opposing the inner end of the carrier.

In testimony whereof, I affix my signature hereto.
